[57] CLAIM

The ornamental design for a wall and ceiling scrubber, as shown and described.

DESCRIPTION

FIG. 1 is a front, top and side perspective view of the wall and ceiling scrubber showing my new design; FIG. 2 is an end elevational view thereof, the opposite end being a mirror image of the end shown in FIG. 2; FIG. 3 is a front elevational view thereof, the rear being a mirror image of the front shown in FIG. 3; FIG. 4 is a top plan view thereof; FIG. 5 is a bottom plan view thereof; and, FIG. 6 is an enlarged, fragmentary perspective view thereof shown with the pivoting arms extended and the head in folded condition.

FIG. 1

FIG. 2

FIG. 3

FIG. 4

FIG. 5

FIG. 6
